BY Victor J. Evans

ATTORNEY

UNITED STATES PATENT OFFICE.

HENRY MARSHALL, OF NEW YORK, N. Y., ASSIGNOR OF ONE-HALF TO EDMUND V. GRIMES, OF NEW YORK, N. Y.

HAND-RUBBER.

1,255,101.

Specification of Letters Patent. Patented Jan. 29, 1918.

Application filed July 10, 1917. Serial No. 179,743.

To all whom it may concern:

Be it known that I, HENRY MARSHALL, a citizen of the United States of America, residing at New York city, in the county of New York and State of New York, have invented new and useful Improvements in Hand-Rubbers, of which the following is a specification.

This invention relates to hand rubbers and has for its principal object the provision of a device of this character which is designed for use in connection with laundry apparatus such as wash boards or the like and is designed to grip a mass of clothes and maintain an arrangement of the same relatively to the rubbing surface of a wash board whereby the clothes can be thoroughly worked over the surface of the board without necessitating the bringing of the hands of the operator in contact therewith.

Another object of the invention is to provide a device of this character in which a novel form of clamp is employed for holding the clothes in engagement with the rubbing surface of the device, the same being adjustable whereby to accommodate itself to various conditions.

With the above and other objects in view which will appear as the nature of the invention is better understood, the same consists in the improved construction and novel arrangement of parts which will hereinafter be fully described and particularly pointed out in the claim.

In the accompanying drawings, has been illustrated, a single and preferred form of the invention, it being, however, understood that no limitations are necessarily made to the precise structural details therein exhibited, but that changes, alterations and modifications within the scope of the claim may be resorted to when desired.

Figure 1, is a perspective view of the device.

Fig. 2, is a transverse section therethrough.

Fig. 3, is a longitudinal section through a portion of the device showing the manner of adjustably associating the clamp therewith.

The device consists of a block or head 1, having rigid handles 2—2, at its ends which are designed to be grasped by the hands of the operator in order that the head 1, can be arranged substantially in flat contact

with the rubbing surface of an ordinary wash board. The said head is provided upon its opposite sides with elastic rubbing elements 3 and 4, the former having longitudinal ribs 5, and the latter short and needle like projections 5. The element 4, is rendered more pliable than the element 3, in the formation of the said needle like projections and it is therefore better adapted to be used when washing delicate fabrics. 65 The element 3, which is provided with the continuous longitudinal ribs is better designed for coarser or heavier fabrics. In either instance it is intended to construct these elements of suitable yieldable material 70 which will serve to grip the clothes and yieldingly support the same against the rubbing surface of a wash board as the device is reciprocated up and down.

In order that a mass of clothes may be 75 held in engagement with either one of the elements 3 or 4, a clamp 6, is employed, the same having a longitudinal branch 7, which is disposed in parallel relation to the adjacent side of the head 1, and parallel side 80 arms 8—8, which slidably extend through passages 9—9, formed in said head 1, whereby the said portion 7, of the clamp can be brought into clamping contact with a mass of clothes which are interposed between said head 1, and said portion 7, and arranged under one of the selected elements 3 or 4. The said arms 9—9, are provided with angular extensions 10—10, which are adapted to come in contact with the adjacent edge of the head 1, so as to limit the sliding movement of the clamp in one direction and positively prevent the side branches of the clamp from escaping from their guide passages 9—9. The extensions 10, are disposed adjacent to the hand grips 2, so that they may be engaged by the hand, and the clamp 6, equally and conveniently released from engagement with the clothes. The said clamp is constructed from a single piece of 90 wire and is preferably covered with a continuous piece of rubber tubing. Said rubber tubing acts to induce friction between the head 1, and the arms 8—8, whereby to securely cause the clamp to maintain a fixed 95 position against the clothes when the device is in operation. It thus follows that the clamp is adapted to be adjusted to many different positions according to the bulk or mass of clothes to be accommodated between 100 105 110

the bar 7, and the adjacent edge of the head 1, as will be understood.

In use the clothes to be operated upon are placed under the head 1, and terminally extended between the bar 7, and said head. The clamp is then adjusted so as to bring the bar 7, in clamping engagement with the clothes. The device is then ready to be reciprocated up and down over the rubbing

surface of an ordinary wash board or similar washing apparatus. In use the device has been found to save considerable labor; the clothes can be thoroughly washed in a comparatively short time and comparatively little injury is done to the hands of the operator. Through the arrangement described, the hands can be held out of direct contact

What I claim is:

A hand rubber comprising a head having a rubbing surface, hand grips at the ends of the head, and a clothes clamp carried by the head and comprising a bar parallel with one side of the head and side branches having parallel side arms freely sliding through the head and provided with angular extensions adapted to coact with the head to limit the sliding movement of the clamp relatively to the head, and an elastic tubing fitting all portions of the bar and serving to induce friction between the side branches and said head to assist in holding the clamp in a relatively fixed position when engaged with the clothes.

In testimony whereof I affix my signature,

HENRY MARSHALL.
